DEVICE AND METHOD FOR PLEATING MATERIAL

Philomena M. Tubbs, Chicago, Ill.

Application July 24, 1952, Serial No. 300,578

5 Claims. (Cl. 223—35)

This invention relates to the pleating of material and 15 more particularly to a device and method for forming pleats in draperies, curtains and the like.

It is known that means are available for forming pleats in draperies, curtains, etc., but known means require the use of backing materials and other permanent attachments that must be secured to the draperies. Moreover, such arrangements are designed to form pleats or folds in the upper or top portion of the draperies, and there is no good method or device available for forming pleats in the lower portion of draperies where it is necessary that the draperies look the best.

It is, then, an object of this invention to provide a device and method for forming pleats in draperies and curtains, etc. Another object is to provide a device and a method for simply and easily forming pleats in draperies, etc., while they are hanging and without a need for tacking or sewing the material and without the use of backing arrangements or other permanent attachments. Still another object is to provide a device that may be secured near or adjacent the lower edge of a drapery to secure folds therein while at the same time weighting the drapery to provide an even fold or pleat throughout the length thereof and that may be subsequently removed after the pleats or folds have set. A further object is to provide a coil spring having spaced turns and equipped at each end with a hook, the length of the coil being so related to the diameter that by compressing the coil along one side to interjoin the hooks the opposite side of the turns spread along radially diverging lines to provide relatively wide openings to facilitate the insertion of the folded material between adjacent turns of the coil. Additional objects and advantages will appear as the specification proceeds.

Specific embodiments of my invention are illustrated in the accompanying drawing, in which—

Figure 1 is a perspective view of an embodiment of my drapery pleating device; Fig. 2 is an end view in elevation of the device shown in Fig. 1; Fig. 3 is a perspective view showing the hooked ends interconnected to spread the opposite side of the coil; Fig. 4 is a top plan view showing the hooked ends interconnected and with the folds of a drapery inserted between the spread turns of the coil; Fig. 5 is a top plan view in which the device is in relaxed condition with the folds of a drapery gripped between adjacent turns of the coil; and Fig. 6 is an end view in elevation of another embodiment of the device.

In the illustration, my device for forming pleats in curtains or draperies, etc., consists of a coil spring 10 having spaced apart turns or loops 11. The coil 10 is equipped at one end with a laterally-turned portion 12 forming a hook and at the opposite end with a similarly laterally-turned end portion 13 providing a hook and handle extension 14.

A ribbon of material 16 looped or turned to form the coil 10 may be of any suitable material. For example, a relatively thin ribbon of plastic may be looped to form the coil as illustrated having spaced turns 11. The plastic may be set in this condition so that a spring coil re-

2

sults. Spring wire may be looped to form the coil 10 having the spaced turns 11. The material used is not critical so long as the formed coil may be expanded along one side as illustrated in Figs. 3 and 4 and will spring back to the condition illustrated in Figs. 1 and 5 when the hooked ends are released.

It is preferred that the coil 10 have a uniform diameter throughout the entire length thereof. The length of the coil 10 should be so related with the diameter thereof that when the coil is compressed along one side to join the hooked ends 12 and 13, the opposite sides of the coil will spread so that the turns thereof diverge along radial lines. When the term compressing the coil along one side is used it is meant that the coil is compressed along a line substantially parallel to the longitudinal axis of the coil and lying on the surface of the coil.

If desired, the coil 10 may be colored variously to provide an attractive appearance. If the turns of the coil are provided by a plastic material, the material may first be colored as desired in any known manner. If the coil is metal it may be painted to provide an attractive appearance or the metal may be heat treated or otherwise treated to produce attractive colors. Further, the coil could be embellished or otherwise equipped with figures or designs to improve the appearance thereof.

In Figs. 4 and 5, a drapery 17 having a plurality of folds 18 therein at desired points is shown with the folds 18 inserted between adjacent turns 11 of the coil 10. Fig. 4 illustrates the desired position of the coil 10 for insertion of the folds 18. Fig. 5 illustrates the coil 10 in relaxed condition wherein the adjacent turns 11 grip the folds 18 to secure the drapery in folded condition.

In Figs. 1 and 2, the hooks 12 and 13 are circumferentially spaced apart so that a slight torsional force must be imparted to the coil 10 as well as compressing the ends thereof, in order to join the hooks 12 and 13. In the form illustrated in Fig. 6, the hooks 12a and 13a of the coil 10a are longitudinally aligned and to join the hooked portions it is only necessary to compress the coil along one side thereof. The handle 14 or 14a provides a ready means for quickly and easily joining the hooks 12 and 13 or 12a and 13a. The handle is also very useful for releasing the hooks after the drapery folds 18 have been inserted between the turns of the coil.

By using my device the method of forming pleats or folds in draperies, etc., is extremely simple. After the draperies are hung in proper position a drapery may be folded upon itself at desired points to provide the most attractive appearance. The coil 10 is then compressed along one side or along a line lying on the surface of the coil and in parallel alignment with the longitudinal axis thereof to cause the adjacent turns 11 to spread apart along radially diverging lines. The coil 10 may be secured in this position by interconnecting the hooks 12 and 13, and for this purpose handle 14 may be grasped between the fingers to draw the hook 13 under the hook 12 to secure the two. The folds 18 in the drapery 17 are then inserted between the spread turns 11 of the coil and may be moved inwardly between the turns until the converging inner portions of the turns offer substantial resistance to the movement of the folded material. The hooks 12 and 13 are then released and the coil 10 assumes the relaxed condition illustrated in Fig. 5. In this position the turns 11 tightly grip the folds 18 and insure retention of the folds at the desired points on the drapery.

It is preferred that the coil 10 be secured to the drapery 17 along the lower or bottom edge thereof, so that the weight of the coil 10 provides a slight pull on the drapery throughout the entire length thereof and thereby aids in creating an even and attractive fold or pleat throughout the entire length of the drapery. Al-

though the turns 11 of the coil grip the folded portions 18 of the drapery rather tightly after the coil has been returned to relaxed condition, the coil may be moved along the folds 18 of the drapery to the desired position or to the position where it is desired to produce the most attractive and well formed pleats.

After the coil or pleat forming device 10 has been positioned upon the drapery 17 to secure the folds 18 therein for a substantial period of time, usually over night, the humidity in the air is ordinarily sufficient to set the folds 18 in the drapery and the coil may then be removed by slipping it free of the pleats. The pleats are found to be accurately set to produce a very attractive pleated drapery. The pleat forming device or coil 10 is then available for pleating other material in a similar manner.

I have found particularly when the draperies are of thin material, or in forming pleats or folds in curtains, that the material may be folded and inserted between the turns 11 of the coil spring 10 without first compressing the coil along one side thereof. However, I prefer to compress the coil and interconnect the hooks 12 and 13, since insertion of the material between the turns is thereby facilitated.

Where the hooks 12 and 13 are peripherally spaced, as in Figs. 1 and 2, it is found that upon interconnecting the hooks the turns 11 of the coil spread apart more widely than when the hooks 12 and 13 are axially aligned as illustrated in Fig. 6. The material then may be more easily inserted between adjacent turns of the coil. It is necessary that the length and diameter of the coil be related to each other so that the turns of the coil spread when the hooked portions are interconnected. The diameter may be varied as required or desired, so long as the length of the coil corresponds thereto. I have found that a coil having a diameter of between 1½ inches and 2½ inches and having lengths up to 6 inches has proved very effective. It is understood, of course, that these dimensions are given by way of example and they may be altered as desired.

While in the foregoing specification I have set forth specific embodiments of my method and device, it is understood that the considerable details set forth for purposes of illustration may be varied greatly by those skilled in the art without departing from the spirit of my invention.

I claim:

1. In a method of pleating material, the steps of providing an elongated coil spring having a plurality of turns that are readily spread apart, providing a body of material to have pleats formed therein, folding said material in pleat fashion at selected points spaced axially along said spring, inserting each of the folds between adjacent turns of said spring whereby the folds are resiliently gripped and held in place, and after the folds have set to form pleats, removing said spring.

2. In a method of pleating material, the steps of providing an elongated coil spring having a plurality of turns

that are readily spread apart, providing a body of material to have pleats formed therein, folding said material to form a pleat first at one point, spreading selected adjacent turns of said spring and inserting the pleat therebetween and thereafter folding said material to form pleats and inserting the same between spread adjacent turns of the spring at other points therealong, allowing the pleats to be resiliently held between adjacent turns of the spring until the pleats have substantially set, and then releasing the pleats from the spring.

3. In a method of setting pleats in freely hanging material, the steps of providing a coil spring having a plurality of turns that are readily spread apart in fan-like fashion, compressing said spring along one side thereof to fan the same and spread apart the turns along the other side thereof, folding the hanging material to form pleats therein, inserting each of the pleats so folded between the spread adjacent turns of said spring, releasing the compressed side of the spring whereby said pleats are resiliently gripped by a self-adjusting force and said spring is supported solely by said material, allowing said pleats to set, and thereafter removing said spring from said pleats.

4. A device for pleating materials, comprising an elongated coil spring having relatively small tensile strength so that adjacent turns thereof are readily spread apart, and interlocking hook members carried by said coil spring adjacent the ends thereof, the length of said coil spring being determined to establish a relationship such that when said hook members are interconnected, adjacent turns of the spring fan outwardly and into spread relation along one side thereof, said coil spring having sufficient stiffness to maintain itself without support in such fanned condition.

5. A device for pleating materials, comprising an elongated coil spring of relatively large diameter and having relatively small tensile strength so that adjacent turns thereof are readily spread apart, said spring being equipped at the ends thereof with integral, interlocking hook members, the hook members at opposite ends of said spring being aligned along a longitudinal line substantially parallel to the longitudinal axis of said spring whereby when said hooks are interconnected, said spring is compressed along one side thereof without twisting force being applied thereto, the length of said coil spring being determined so that adjacent turns of the spring fan outwardly and into spread relation along one side thereof when said hook members are interconnected, said spring having sufficient stiffness to maintain itself, when unsupported, in such fanned condition.
